(57) CLAIM

The ornamental design for a pedicure spa, as shown and described.

DESCRIPTION

FIG. 1 is a perspective view showing the front, right side and top views of my new pedicure spa showing my new design; FIG. 2 is a perspective view showing the rear, left side and top views thereof;

FIG. 3 is a top plan view thereof;

FIG. 4 is a right side elevation view thereof; the left side elevation view is the same as the right side elevation view, such as that shown in FIG. 4;

FIG. 5 is a front elevation view thereof; and,

FIG. 6 is a rear elevation view thereof.

The broken line showing of parts of the drawings is included for the purpose of illustrating use and environment and forms no part of the claimed design.
